UNITED STATES PATENT OFFICE

HERMAN H. SMITH, OF BROOKLYN, NEW YORK

METALLIZED WALKWAY SURFACE

Application filed April 3, 1926. Serial No. 99,454.

This invention relates to improvements in pavements and is particularly applicable to walkway surfaces as sidewalks, stairheads, curbing, railway platforms, etc. wherein a material having an exposed top surface or exposed top and side surfaces is employed.

It is one of the primary objects of the invention to provide a metallic tread or surface plate for protecting the exposed parts 10 of such material by means of a metallic unit embedded directly in the pavement material.

It is a further object to provide an improved metallic unit with means for exposing the pavement material through and around 15 the same to firmly anchor the unit with respect to the pavement material so that further attention will not be required after the unit is once inserted in position in the pavement material.

20 It is a further object to provide a metallized walkway surface, composed of a metal unit so designed as to expose a filling material between the bars of the metal unit, the said filling material being composed of elements 25 which will endure heavy wear, prevent slipping, and fuse firmly with the paving material in which the metallic unit is embedded.

It is still a further object to provide a particular anchoring element for use with said 30 unit.

These and other objects will appear more fully from the following description when considered in connection with the drawings in which:

35 Fig. 1 is a plan view of a portion of a tread plate secured in position in a pavement material.

Fig. 2 is a vertical sectional view thereof substantially on the line 2—2 of Fig. 1.

40 Fig. 3 is a transverse sectional view on the line 3—3 of Fig. 1.

Fig. 4 is a perspective view of one of the removable anchoring extensions employed.

45 Figs. 5 and 6 show certain modifications in the configuration of the tread plate which may be employed.

Fig. 7 shows one adaptation of the invention.

50 Fig. 8 is a sectional view of a different adaptation of the invention taken substan-

tially on the line 8—8 of Fig. 9, representing the preferred form of unit used for steps or the like.

Fig. 9 is a plan view of the structure shown in Fig. 8, parts being in section.

Fig. 10 is a plan view of one form of surface plate which may be employed with curbs.

Fig. 11 is a front elevational view of the tread plates shown in Fig. 10.

Fig. 12 is a vertical sectional view taken 60 on the line 12—12 of Fig. 10; and

Fig. 13 is a similar view showing a slight modification of the unit disclosed in Fig. 12.

Referring first to Figs. 1 to 4 there is disclosed the general construction of the tread plate which may be used on stair treads, curbings or the like formed of any preferred pavement material such as concrete. In general in the specification and claims the material forming the body of such steps or curbstones 70 is referred to as the pavement material, it being understood that by this term I mean to identify any material used in the formation of stair treads or curbstones or other tread units having exposed edges.

Referring to the details of the drawings, the pavement material indicated generally by the numeral 14 has secured thereon and embedded therein a metallic unit 16 for protecting the upper surface and said edges of 80 the pavement material as will appear more fully below. The unit 16 in this form of the invention is provided with a tread portion 18 formed with longitudinal openings 19 through which the pavement material may 85 be exposed substantially flush with the upper surface of the tread portion 18. The openings 19 may be relatively long compared with the width of the same, as indicated for

example in Fig. 1, the side edges of the openings preferably diverging upwardly as shown in Fig. 3, to provide a wedge-shaped body of pavement material as indicated at 20 for firmly anchoring the metallic units to the pavement material. In some circumstances 90 as where there is extremely heavy wear upon the tread portion of the unit, it is preferred to make use of an especially prepared pavement material or cement for filling the openings 19, this cement being laid before the 100

body of the pavement material 14 has become firmly set and fusing or merging into the main pavement material 14. The surface of the pavement exposed through the openings 19 as indicated for example at 20 may accordingly be formed of sand, Portland cement and carborundum resulting in an exposed pavement material which will withstand extremely long wear and having a high coefficient of friction will be practically non-slipping. The upper surface of the unit 16 and in particular the surface of the tread portion 18 is preferably formed with a series of depressions or grooves 21 extending lengthwise of the unit between the openings 19 for providing a further anti-skid wearing surface for the unit. The portions of the units between the openings 19 form cross-members 22 for strengthening the units, these cross-portions 22 being apertured as indicated at 23 for receiving the anchoring extensions as described below.

The anchoring extensions indicated generally at 24 are shown as removably secured to the units 16 and to this end are provided with threaded reduced extensions 25 adapted to be threadedly engaged within the openings 23 of the units 16. The extensions 24 are provided with body parts 26 forming shoulders 27 for engagement with the units 16 and with enlargements 28 at the free portions of the extensions preferably wedge-shaped in form to facilitate the insertion of the anchoring extensions into the pavement material. The side surfaces of the body portions 26 preferably taper from the enlargements 28 to the shoulders 27, the body portion so formed being wedge-shaped for more securely anchoring the extensions in the pavement material. In order to provide for continuity of the pavement material through as well as around the extensions, they are shown as provided with transverse apertures 30 for receiving the pavement material. The upper surfaces of the enlargements 28 serve to securely anchor the extensions 24 and units 16 in the pavement material.

While it is preferred to provide upwardly diverging openings 19 as indicated in Fig. 3, these openings may be formed as shown in Figs. 5 or 6, Fig. 5 disclosing the openings as downwardly diverging and in Fig. 6 the openings have substantially parallel sides. It is to be understood that variations in this respect may be accepted without departing from my invention.

In Fig. 7 I have shown one use to which my invention may be applied, namely for a surface for an exposed pavement material such as steps or curbings in which a very slight extension over the edge of the pavement material is desired. The body part 16^a of the units is formed as shown in Figs. 1 to 3, the extension 32 forming a corner bead for the pavement material, the units protecting

the top surface and corner or edge of the pavement material.

In Figs. 5, 8 and 9 there is disclosed one of the preferred forms of my invention in which the tread portion 18^b of the unit 16^b is formed as disclosed in Figs. 1 to 3 but in which a vertical side extension 34 is provided for protecting the side surface of the pavement material 14^b, the unit being embedded in such pavement material as in the first form of the invention. The side extension 34 is preferably apertured as indicated at 19^b thus exposing the pavement material through the extension for better anchoring the unit in position. The extensions 34 as well as the tread portions 18^b of the units may be provided with anchoring extensions 24 for resisting upward or outward movement of the units with respect to the pavement material, it being understood that the extension 24 shown in Figs. 8 and 9 is substantially the same as that disclosed in Figs. 1 to 4 and that any preferred number of such extensions may be used for firmly anchoring the units to the pavement material.

In Figs. 10, 11 and 12 there is disclosed one form of curb protector 16^c wherein the tread portion 18^c is provided with the apertures 19^c as in the first form of the invention, for exposing a pavement material. The unit 16^c forms in effect an entire cap for protecting the upper surface and side edges of the curb. The front edge of the unit, that is, the edge placed adjacent to the street, the surface of which is indicated at 36, is preferably formed with the enlarged rounded corner 38 terminating in the side extension 34^c. The extension 34^c, as shown, has a wedge-shaped point 39 for facilitating the insertion of the unit into the concrete or other curb 14^c while the latter is in a plastic or semi-plastic state. The side extension 34^c is preferably apertured as indicated at 19^c for exposing the pavement material as in the other forms of the invention. The rearward surface of the curbstone may be protected and the unit more firmly anchored into the material of the curbstone by providing a relatively small rearward extension 40 provided with a reduced point 41 for facilitating its introduction into the pavement material and with elongated apertures 19^c for exposing the pavement material through the said rearward extension. If desired one or more anchoring extensions 24 may be secured to each of the units 16^c for anchoring them with respect to the pavement material as disclosed fully above.

It will be seen that the upper surface and the proximate side surfaces of the curb provided with the units 16^c will be amply protected against injury due to traffic or other wear on or against the curbstone. This result is attained in part by reason of the continuous or unbroken character of the corners forming

the junction of the top and side portions of the unit. The units are firmly anchored with respect to the curb by reason of the apertures 19^c exposing the pavement material through both side projections 34^c and 40 and through the upper surfaces 18^c, the openings in the upper surfaces 18^c receiving a wedge-shaped body of pavement material as indicated. The units 16^c are particularly useful for curbings because of the fact that they are substantially of the same width as the curb and can be inserted in position between the sides of the form or mold being used for forming the curb, that is, as soon as the concrete 14^c has been poured the units 16^c may be inserted in place between the sides of the form for the curb and firmly embedded in the material 14^c while the latter is in a plastic or semi-plastic state, with the result that the units 20 form substantially an integral part of the curb.

In Fig. 13 I have shown a slight modification of curb protector which may be employed, the unit therein disclosed being constructed similarly to that shown in Figs. 10, 11 and 12 except that a projecting bead 42 is formed at the edge of the unit adjacent the street side of the curb for preventing the wheels of vehicles from scraping upon the curb proper. The side extension 34^d of the unit disclosed in Fig. 13 is accordingly slightly enlarged relatively to the size of the extension 34^c shown in Figs. 11 and 12 and is apertured as indicated at 19^d for the purposes given above.

It is to be understood that the pavement material referred to in the specification and claims may be of any preferred type and that the unit is applicable to variations in the specific pavement material utilized. The invention herein disclosed is particularly applicable for metallizing any type of exposed construction material such as sidewalks, curbstones, steps, walls, floors, platforms, etc., such materials being indicated generally by the term "pavement material".

This invention constitutes an improvement upon the pavement disclosed in my patent No. 1,560,354, reference being had to this patent for the general objects and advantages of the paving unit herein disclosed.

Having now described my invention I desire it to be understood that the embodiments herein disclosed are merely illustrative of the basic principle of the invention and that I am to be limited only as set forth in the claims hereunto appended.

I claim:

1. In combination with a pavement material, a metallic unit adapted to be moulded into said pavement material and formed with a tread portion and an edge extension exposed at the top surface and a side surface respectively of said pavement material and an anchoring extension projecting

inwardly from said unit into said pavement material, said anchoring extension being provided with a wedge shaped enlargement near the free end thereof and formed with a reduced inner or forward edge and an outwardly projecting securing shoulder.

2. In combination with a pavement material, a metallic unit adapted to be moulded into said pavement material and formed with a tread portion and an edge extension exposed at the top surface and a side surface respectively of said pavement material and an anchoring extension projecting inwardly from said unit into said pavement material, said anchoring extension being provided with a transverse opening extending therethrough and formed with an enlarged head adjacent the free end thereof.

Signed at New York, in the county of New York, and State of New York, this 30th day of March, A. D. 1926.

HERMAN H. SMITH.
